UNITED STATES PATENT OFFICE.

HARRY G. WEBSTER, OF CHICAGO, ILLINOIS.

RECEIVER.

Application filed June 7, 1923, Serial No. 643,890. Renewed January 11, 1928.

My invention relates to receivers of the type used for the reception of telephonic currents, an object being to provide an improved arrangement of the above character having 5 certain features of construction and operation more particularly pointed out in the ensuing part of the specification and appended claims.

In the accompanying drawings I have 10 shown several forms of my invention, in which—

Fig. 1 shows a preferred arrangement of receiver mechanism and is a cross sectional view through the device;

15 Fig. 2 is a top plan view showing the interior of Fig. 1 with the ear piece and diaphragm removed;

Fig. 3 is a cross sectional view along the line 3—3 of Fig. 2;

20 Fig. 4 shows a crystal detector circuit adapted for use in combination with the receivers of Figs. 2, 6 or 7;

Fig. 5 shows a tuned circuit of the audion tube type adapted for use in combination 25 with the receivers of Figs. 1, 6 or 7;

Fig. 6 shows another form, in which the armature of the receiver mechanism is directly connected to a microphone button;

Fig. 7 is another form of receiver mechanism operating as a loud speaker for radio 30 equipment and in which the armature controlling magnets are electrically controlled; and

Fig. 8 shows a magnet structure in which 35 the two permanent magnets are connected together as a single unit of magnetizable material as distinguishing from the form of Figs. 1 to 3 where the separator is of non-magnetic material.

40 Referring now to the form of receiver shown in Figs. 1, 2 and 3, a suitable enclosure A is employed, comprising a casing 10 and ear piece 11 between which is clamped in a suitable manner a diaphragm 12.

45 For operating the diaphragm 12 I preferably employ an electromagnet having a reciprocatory armature so mounted that its polarity is reversed with reversals of current in the electromagnet coil and associated with mag-

50 nets, in this form permanent magnets, preferably of the horseshoe type, positioned on opposite sides of the armature so that the armature will be attracted toward one or the other, as the direction of voice currents through the electromagnet coil vary.

The electromagnet comprises a suitable

coil or helix consisting of winding 13—14, said winding being preferably arranged so that an armature 15 may extend therethrough and be affected by the voice currents 60 traversing the coil. The winding terminates at connectors 23, 24 so that it may be connected to the desired circuit. The armature 15 is preferably supported so that it may move independent of its energizing coil 13—14, 65 so as to reduce the inertia and momentum thereof to a minimum, and I preferably support the armature so that it moves bodily to actuate the diaphragm 12. A connecting stem 16 extends from the armature 15 to the 70 diaphragm 12, being clamped to the diaphragm by means of suitable nuts 17. In order to assist in supporting the armature 15, and also maintain the diaphragm 12 under a normal tension, I provide a spring 18 adjustably supported in the bridge piece 19 so as to be able to vary the tension thereof according to the adjustment required.

To control the operations of the armature 15 I provide magnets to attract the armature 80 one way or the other, according to the direction of current in its coil. I employ magnets which are maintained permanently magnetized during the use of the device either as electromagnets or so called permanent magnets. 85 In the device of Figs. 1 to 3 I employ permanent horseshoe magnets 20—21 positioned on opposite sides of the armature and with opposite pole ends of opposed polarity. This is indicated in Fig. 1 where the magnets are 90 marked to indicate their polarity, N indicating a north pole and S a south pole.

With this arrangement, in the operation of the device of Figs. 1, 2 and 3, the diaphragm operating armature 15 has its polarity varied 95 as the voice currents traversing the coil vary. Thus with the voice current traveling in one direction, the armature is attracted toward one permanent magnet, and repelled by the other permanent magnet, and with the current reversed the armature is attracted toward the other magnet and repelled by the opposite magnet.

Thus as the voice currents are impressed upon the operating electromagnet coil, the 105 armature 15 vibrates in accordance with the variations of these voice currents, to operate the diaphragm 12 accordingly.

The receiver mechanism of Figs. 1 to 3 is adapted for all telephonic uses and may be 110 used to advantage in connection with radio receiving systems. Thus it may be connected

in combination with the crystal detector circuit of Fig. 4, or it may be used in combination with a tuned circuit of the audion tube type as shown in Fig. 5. When used with Fig. 4 the terminals 23—24 of the receiver are connected to terminals 33—34; and when used with the tuned circuit of Fig. 5 the receiver terminals are connected across the terminals 43—44.

10 In Fig. 6 I have shown a modified form of apparatus in which the device acts as a voice current repeater by having the receiver armature operate a connected microphone 27. I have shown the microphone 27 connected 15 in circuit with a receiver A, which is indicated as of the type shown in Figs. 1 to 3 but of course may be of any other approved design. Or the microphone may be connected in circuit with a loud speaker A', which 20 may be of the type of apparatus shown in Figs. 1 to 3 with an amplifying horn.

The arrangement of Fig. 6 is particularly useful in connection with radio equipment such as a crystal set where the current received is not amplified but transmitted directly to the helix of the receiver and then amplified through the use of the connected microphone. It is to be understood, however, that I also contemplate using the arrangement of Fig. 6 with a tuned circuit of the audion tube type shown by way of illustration in Fig. 5 where the terminals 23—24 of the receiver mechanism are connected to terminals 43—44 of Fig. 5.

35 In Fig. 7 I have shown another modified form of my invention, in which the armature controlling magnets are electrically magnetized. To this end the magnets comprise suitable cores 20' and 21' with windings 40 thereon so arranged and so connected with a source of current 25 that they are polarized with opposed pole-faces of opposite polarity. In the drawing this is indicated by the letters N and S, as in Fig. 1. The strength of 45 these magnets 20' and 21' may be varied in a suitable way, as for instance by adjusting the resistance 30. The armature 15 in this receiver is shown as connected to a diaphragm 12 and amplifying horn 28 of a loud speaking 50 construction.

The receiver mechanism of Fig. 7 may be employed in combination with the crystal receiving set of the character illustrated in Fig. 4 for example, or it may be connected 55 with a tuned circuit of the audion tube type shown in Fig. 5 by way of illustration. When used in either combination it may be adjusted so as to secure the most effective and desirable results.

60 Although in Fig. 6 I have shown permanent magnets 20—21 and in Fig. 7 electromagnets 20'—21', it will be apparent that either type of magnet may be used in the receiver of each figure.

65 In Fig. 8 I have shown a unit construction,

wherein the two magnets are mechanically united preferably at their neutral points by magnetic material; this provides an integral magnetic structure, rather than it being separate magnets as in the construction illustrated in Figs. 1 and 3. The Fig. 8 construction, nevertheless, provides two independent magnetic circuits with which the armature 15 is correlated; and in this respect is like the construction illustrated in Figs. 1, 2 and 3. 75

Although I have shown preferred forms of my invention, I contemplate using it in other ways than that illustrated, and therefore do not desire to be limited to these precise forms but aim to cover all that which comes within the spirit and scope of the appended claims. 80

What I claim as new and desire to secure by United States Letters Patent is:

1. In a receiver of the character described, an electromagnet having a reciprocatory armature the polarity of which is reversed with reversals of current in the electromagnet coil, and two magnets positioned each on a side of the armature opposite the other, whereby the armature is attracted toward one or the other of the magnets according to the polarity of the armature, and sound producing means actuated by said armature. 90

2. In a receiver of the character described, an electromagnet having a reciprocatory armature the polarity of which is reversed with reversals of current in the electromagnet coil, and two magnets positioned each on a side of the armature opposite the other, whereby the armature is attracted bodily toward one or the other of the magnets according to the polarity of the armature, and sound producing means actuated by said armature. 100

3. In a receiver of the character described, an electromagnet comprising a helix and core movably supported in the helix and whereby the electro-magnetic field including the core may be reversed with reversals of current in the helix, and a pair of magnets each positioned with a pole-face operatively associated with each end of the core, the magnets having opposing polarities at each end of the core, whereby the core is moved in one direction or another according to the direction of current in the helix, and sound producing means actuated by said armature. 105

4. In a receiver of the character described, an electromagnet comprising a helix and core supported to reciprocate bodily transversely of the axis of the helix and whereby the electro-magnetic field including the core may be reversed with reversals of current in the helix, and a pair of magnets each positioned with a pole-face operatively associated with each end of the core, the magnets having opposing polarities at each end of the core, whereby the core is moved in one direction or another according to the direction of current in the helix. 120

5. In a receiver of the character described, 125

- two magnets oppositely disposed with opposite pole-faces of opposed polarity, an electromagnet having a movable core the polarity of which is reversed with reversal of current in the electromagnet coil and positioned between the opposed pole-faces of the magnets so as to be attracted by one or the other of the magnets according to the polarity of the armature and thereby provide an increasing 10 magnetic path for the magnet attracted to.
6. In a receiver of the character described, two permanent horse-shoe magnets oppositely disposed with opposite pole-faces of opposed polarity, an electromagnet having a 15 movable core the polarity of which is reversed with reversal of current in the electromagnet coil, and positioned between the opposed pole-faces of the magnets so as to be attracted by one or the other of the magnets according 20 to the polarity of the armature, and repelled from the pole-faces of the other magnet.
7. In a receiver of the character described, two permanent horse-shoe magnets oppositely disposed with opposite pole-faces of 25 opposed polarity, an electromagnet having a movable core the polarity of which is reversed with reversal of current in the electromagnet coil, and positioned between the opposed pole-faces of the magnets so as to be attracted by 30 one or the other of the magnets according to the polarity of the armature, and repelled from the pole-faces of the other magnet, and provide an increasing magnetic path for the magnet toward which it is attracted and a 35 decreasing magnetic path for the magnet from which it is repelled.
8. In a receiver of the character described, an electromagnet having a reciprocating armature extending through the helix thereof 40 so that the magnetic flux will vary in the armature with variations of voice currents impressed upon the helix and two magnets oppositely disposed relative to the armature and to each other whereby the armature is 45 attracted toward one or the other of the magnets as the magnetic flux in the armature varies, and sound producing means actuated by said armature.
9. In a receiver of the character described, 50 an electromagnet having a reciprocating armature extending through the helix thereof so that the magnetic flux will vary in the armature with variations of voice currents impressed upon the helix, and two magnets 55 oppositely disposed relative to the armature each positioned with a pole-face operatively associated with each end of the armature, the magnets having opposing polarities at each 60 end of the armature, whereby the armature is attracted toward one or the other of the magnets as the magnetic flux in the armature varies.
10. In a receiver of the character described, 65 an electromagnet having a reciprocating armature extending through the helix thereof so that the magnetic flux will vary in the armature with variations of voice currents impressed upon the helix, two magnets disposed one on each side of the armature, the helix of the electromagnet and the polarity 70 of the magnets being such as to cause the armature to be attracted toward one magnet and repelled by the other and vice-versa, with the variations of the magnetic flux in the armature, and sound producing means actuated by said armature.
11. In a structure of the character described; a receiver including an electromagnet having a reciprocating operating armature the polarity of which is reversed with 75 reversals of current in the electromagnet coil by voice currents impressed thereon, and two magnets positioned each on a side of the armature opposite the other, whereby the armature is attracted toward one or the other 80 of the magnets according to the polarity of the armature; and a repeating amplifier including a microphone having an electrode mechanically connected with and operated by the receiver armature for repeating the voice 85 current operations of the receiver armature.
12. In a receiver of the character described, an electromagnet having a reciprocating armature the polarity of which is reversed with 90 reversals of current in the electromagnet coil, and two magnets positioned each on a side of the armature opposite the other, whereby the armature is attracted toward one and repelled by the other of the magnets, and vice versa, according to the polarity of the 95 armature, and sound producing means actuated by said armature.
13. In a receiver of the character described, an electromagnet having a reciprocating armature the polarity of which is reversed with 100 reversals of current in the electromagnet coil, and two magnets positioned each on a side of the armature opposite the other, whereby the armature is attracted bodily toward one and repelled by the other of the magnets, and vice 105 versa, according to the polarity of the armature, and sound producing means actuated by said armature.
14. In a receiver of the character described, an electromagnet comprising a helix and 110 core movably supported in the helix and whereby the electro-magnetic field including the core may be reversed with reversals of current in the helix, and a pair of magnets each positioned with a pole-face operatively 115 associated with each end of the core, the magnets having opposing polarities at each end of the core, whereby the core is attracted by one magnet and repelled by the other, and vice versa, according to the direction of current in the helix, and sound producing means actuated by said core.
15. In a device of the character described, 120 magnetic operating mechanism therefor including two independent magnetic circuits 125
- 130

composed of opposite magnetic poles arranged in pairs, a helix in the field of force of said poles having its axis parallel to said pairs, an armature within said helix acting 5 to vary inversely the reluctance of the magnetic circuits of said pairs responsive to variations of voice currents impressed upon the helix.

16. In a device of the character described, 10 magnetic operating mechanism therefor including two independent magnetic circuits composed of opposite magnetically connected poles arranged in pairs, a helix in the field of force of said poles having its axis parallel to said pairs, an armature within said helix acting to vary the reluctance of the magnetic circuits of said pairs responsive to variations of voice currents impressed upon the helix.
17. In a device of the character described, 15 magnetic operating mechanism therefor including two independent magnetic circuits composed of opposite magnetically connected poles arranged in pairs, a helix in the field of force of said poles having its axis parallel to said pairs, an armature within said helix acting to vary inversely the reluctance of the magnetic circuits of said pairs responsive to variations of voice currents impressed upon the helix.
18. In a device of the character described, 20 magnetic operating mechanism therefor including two independent magnetic circuits composed of opposite magnetic poles arranged in pairs, a helix in the field of force of said poles having its axis parallel to said pairs, an armature within said helix acting to vary inversely the reluctance of the magnetic circuits of said pairs responsive to variations of voice currents impressed upon the helix.
19. In a device of the character described, 25 magnetic operating mechanism therefor including two independent magnetic circuits composed of opposite magnetic poles arranged in pairs, a helix in the field of force of said poles having its axis parallel to said pairs, an armature within said helix acting to vary inversely the reluctance of the magnetic circuits of said pairs responsive to variations of voice currents impressed upon the helix.
20. In a device of the character described, 30 magnetic operating mechanism therefor including two independent magnetic circuits composed of opposite magnetic poles arranged in pairs, a helix in the field of force of said poles having its axis parallel to said pairs, an armature within said helix acting to vary inversely the reluctance of the magnetic circuits of said pairs responsive to variations of voice currents impressed upon the helix.

21. In a device of the character described, 35 magnetic operating mechanism therefor including two independent magnetic circuits composed of opposite magnetic poles arranged in pairs, a helix in the field of force of said poles, an armature in said helix movable in one direction responsive to voice currents of one direction impressed upon the helix to decrease the magnetic reluctance of one of said pairs and increase the magnetic reluctance of the other pair, and oppositely effective upon the pairs responsive to voice current of another direction.
22. In a device of the character described, 40 magnetic operating mechanism therefor including two independent magnetic circuits composed of opposite magnetic poles arranged in pairs, a helix in the field of force of said poles, an armature in said helix movable in one direction responsive to voice currents of one direction impressed upon the helix to decrease the magnetic reluctance of one of said pairs and increase the magnetic reluctance of the other pair, and oppositely effective upon the pairs responsive to voice current of another direction.

23. In a device of the character described, 45 magnetic operating mechanism therefor including two independent magnetic circuits composed of opposite magnetic poles arranged in pairs, a helix in the field of force of said poles, an armature in said helix movable in one direction responsive to voice currents of one direction impressed upon the helix to decrease the magnetic reluctance of one of said pairs and increase the magnetic reluctance of the other pair, and oppositely effective upon the pairs responsive to voice current of another direction.

mature the polarity of which is reversed with reversals of current in the electromagnet coil, two magnets positioned each on a side of the armature opposite the other, whereby the armature is attracted toward one or the other 50 of the magnets according to the polarity of the armature, means for adjusting the normal magnetic strength of the two magnets, and sound producing means actuated responsive to said armature.

24. In a receiver of the character described, 55 an electromagnet having a reciprocatory armature extending through the helix thereof so that the magnetic flux will vary in the armature with variations of voice currents 60 impressed upon the helix and two magnets oppositely disposed relative to the armature and to each other whereby the armature is attracted toward one or the other of the magnets as the magnetic flux in the armature 65 varies, an electromagnetic circuit for the two magnets for varying the normal strength thereof, and sound producing means responsive to said armature.

25. In a receiver of the character described, 70 an electromagnet having a reciprocatory armature extending through the helix thereof so that the magnetic flux will vary in the armature with variations of voice currents 75 impressed upon the helix, two magnets oppositely disposed relative to the armature each positioned with a pole-face operatively associated with each end of the armature, the magnets having opposing polarities at each end of the armature, whereby the armature 80 is attracted toward one or the other of the magnets as the magnetic flux in the armature varies, and a circuit for varying the strength of the two circuits including windings for the magnets and a source of energizing current.

In witness whereof, I hereunto subscribe my name this 21st day of May A. D., 1923.

HARRY G. WEBSTER.
